METHOD AND APPARATUS FOR
COMPLETING WELLS

John E. Eckel, Houston, Tex., assignor to Standard Oil Development Company, a corporation of Delaware

Application April 9, 1942, Serial No. 438,243

9 Claims. (CL 166—5)

The present invention relates to a method and equipment for completing an oil well.

For many years it has been known that the productivity of an oil well can be improved by depositing a gravel pack adjacent the exposed face of the producing formation.

Ordinarily in such a completion the producing formation is underreamed to enlarge the surface exposed and the cavity so formed is filled with gravel in which may be embedded a screen carried at the lower end of the producing string. In such completion operations the gravel is usually deposited in loose discrete form. The movement of the lumps of gravel relative to each other exercises a sort of abrading action which causes the producing formation to be worn away with the result that formation material becomes mixed with the gravel and decreases its efficiency. To avoid this difficulty it has been suggested in the past to mix the gravel with a binder of relatively dense plastic material which will prevent formation material from mixing with the gravel until the binder is removed after the gravel is in place.

In addition to gravel packs deposited in reamed-out cavities, as described above, the art has used prepacked liners which are concentric perforated cylinders of different diameters having the annular spaces between them packed with gravel or other aggregate. These liners are lowered into the well opposite the producing formation at the end of the producing string of tubing. Since the gravel in such liner is put in place at the surface and is held stationary until the liner is located in its final position, the possibility of this gravel mixing with formation material is eliminated. Nevertheless, in a great many instances it has been found that after the prepacked liner has been put in place opposite the producing formation it was impossible to effect a passage of formation fluid through the liner.

The present invention is based on the realization that such prepacked liners become plugged in transit from the surface to the producing formation by virtue of the fact that they pass through mud which contains colloidal clay which deposits around the gravel particle and forms a seal, the removal of which is practically impossible. Accordingly, it is the principal object of the present invention to protect the gravel during its transit through the mud column from contamination with the mud. This may be done by mixing with the gravel any filler which will exclude the mud and which may be removed by

the application of heat or a suitable solvent after the liner has been placed opposite the producing formation.

Another object of the present invention is the provision of a mud excluder for a prepacked liner which will not require any special operation for its removal after the liner is in place but will be removed automatically during the completion operations. This objective is achieved by mixing with the gravel a substance which at ordinary temperature is solid or semi-solid and preferably water insoluble or immiscible and which at the temperature at the depth of the producing formation becomes a mobile or viscous liquid which may be removed when it is subjected to a pressure differential. Among materials suitable for this purpose may be mentioned greases, waxes, such as paraffin wax, asphalts and tars, certain natural gums and resins and the like.

20 In a completion operation, in accordance with the preferred embodiment of the present invention, a liner is packed with gravel mixed with a suitable mud excluder, such as cup grease. The liner is of such construction that during its passage downwardly through the mud column the pressure on both sides of the pack is the same. When this condition is observed it is not of great moment that the cup grease may become sufficiently mobile to flow during the travel of the liner downwardly since even if this happens it will not flow because it is immiscible with the aqueous fluid and is not subjected to a pressure differential. When the liner is in place opposite the formation, its lower portion is sealed off by a suitable packer from the upper portion of the hole and the fluid above the liner either in the producing string or in the entire hole is removed by swabbing. This immediately results in having one side of the liner subjected to the pressure of the producing formation while the other side is subjected to atmospheric pressure or a substantially reduced pressure. At the temperature prevailing at the depth of the producing formation the cup grease will be of sufficiently low viscosity to flow and will be forced out of the gravel pack by the pressure differential so created. The oil passing through the filter pack will be miscible with the cup grease and will upon the institution of flow wash out the grease completely from the gravel pack.

The same action occurs when any other mud excluder which undergoes a change of viscosity with temperature is employed. Instead of a material of this type, there is contemplated for the practice of the present invention the use of a gel

which is consumed or deteriorated bacterially over a given period of time. Such gels are described in U. S. Patent No. 1,998,756. In this patent it is proposed to form such gels in situ in a bore hole and then permit them to be removed bacterially. When such gels are used in the practice of the present invention, they are formed at the surface in the gravel packed liner before the latter is introduced into the well and they have incorporated with them suitable bacteria in sufficient amount to liquefy the gel within the desired period of time.

In the practice of the present invention there is also contemplated an operation in which the avoidance of pressure differential on opposite sides of the filter pack until it is properly located need not be observed. For example, in utilizing a mud excluder which has a viscosity which varies with temperature, the temperature of the fluid in the bore hole can be regulated by continuous or periodical circulation so that it will not go below the melting point of the mud excluder until the liner is located adjacent the producing formation and fluid circulation has stopped. Again it is contemplated that the pre-packed liner containing the mud excluder may be provided with a solid refrigerant which will keep the mud excluder solid until the refrigerant is consumed. A suitable refrigerant is dry ice which may be packed into the inner cylinder of the prepacked liner, the latter in this case having its ends sealed off to prevent the aqueous fluid in the well from coming into contact with the dry ice.

The nature and objects of the present invention may be better understood from the following detailed description of the accompanying drawings in which

Fig. 1 is a vertical section in diagrammatic form showing a liner packed according to the present invention being lowered into place;

Fig. 2 is a similar view showing the parts in position for the establishment of a pressure differential across the liner; and

Fig. 3 is a similar view with the parts in producing position.

Referring to the drawings in detail, numeral 1 designates a bore hole, lined with casing 2 which extends to the surface from the producing formation 3 and is cemented in place by cement 4. Suspended in the bore hole is a string of tubing 5 which has at its lower end a liner made up of an outside cylinder 6 and an inside cylinder 7. These liners are concentric and of different diameters whereby there is an annular space between them filled with aggregate 8 mixed with a filler 9. Both cylinders are provided with perforations 10.

The cylinders carry at their lower end a head 11 which has a central passage 12 in one portion of which there is a seat 13 for a valve 14. This valve is in the form of a cup having a central cavity 15 of polygonal shape adapted to receive a head 16 of the same shape carried at the end of the producing string as an integral part of a cap 17 provided with exterior left-hand threads 18. The cup 14 is also provided with exterior right-hand threads 19 and with radial passages 20 connecting the cavity 15 with a space 21 immediately above the seat 13 and below the flange 22 which is threaded to receive threads 19. As will be observed, the cup 14 is also spaced from the seat 13 as to permit flow of fluid from the tubing 5 through the central passage 12 and to be seated on 13 when the tubing is turned to the

right to disengage the threads 18 from the head 11.

The lower end of the producing string is made up of a plurality of joints, in one of which is a coupling sleeve 23 having peripherally spaced vertical slots 24, in each of which is pivoted a pawl 25 normally spring-pressed outwardly.

The upper end of the liner carries a packer 26, the lower end of which is secured to the liner in a known manner, and the upper end of which is connected to a sleeve 27 slidably mounted on the liner and having an internal shoulder 28 adapted to receive the pawls 25.

With the parts in the position shown, the assembly is lowered into the bore hole to the position shown in Fig. 1. In this position both sides of the liner are subjected to the same fluid pressure so that there is no pressure differential across the annular space. Thus, even though the filler be one which may tend to become mobile at the bottom hole temperature, such as cup grease, paraffin, or the like, it will not ordinarily become fluid enough to flow out of the annular space and there will be no pressure differential to move it out. At this point, water is forced down the tubing to wash out the drilling mud with which the hole has been filled. This flushing with water also serves to remove the mud sheath from the producing formation and the outside of the liner. In this connection, it is helpful to use chemicals, such as acids and deflocculating agents, in the wash water, particularly where substances decomposable by acid such as lime have been used in the drilling mud. When the returns show clear, the head 11 is set on the bottom and the tubing 5 is rotated to the right, thereby disengaging threads 18 and screwing down cup 14 until it is seated on the seat 13.

When the cap 17 is disengaged from the head 11, the tubing is raised until the pawls 25 clear the shoulder 28 of sleeve 27. Then the tubing is again set down whereupon the pawls push down the sleeve 27 and press the packer 26 against the casing. This serves to seal off the outside of the liner from the fluid column in the hole and leave it exposed to formation pressure. The formation pressure will then build up outside the liner, thereby creating a pressure differential across the gravel pack which forces the filler out of the pack. This pressure differential can be enhanced by swabbing the tubing and it will usually be advisable to perform the swabbing operation in the tubing in order to start the well flowing.

The parts are shown in Fig. 3 in the position they occupy when the well is flowing. It will be understood that the setting tool at the end of the tubing need not be left in the well since the setting string can be pulled out and the well produced through the casing or through a separate producing string introduced for that purpose.

As has previously been indicated, the apparatus shown in the drawings is illustrated more or less diagrammatically. Greater detail with respect to the liner and packer may be found in any catalogue of oil well supplies. Such equipment is described, for example, on pages 426-433, 1420-1423 and 2287-2293 of the 1942 edition of the Composite Catalogue of Oil Field and Pipe Line Equipment, published by "Oil Weekly."

It will be apparent that changes may be made in the arrangement or the procedure described without departing from the scope of the present invention. Fillers other than those specifically named may be employed and the use of these

fillers may require completion operations in addition to or instead of those specifically described. While such various operations are contemplated, the present invention is preferably practiced by the use of a filler which may be removed by the creation of a pressure differential across the packed annular space.

The nature and objects of the present invention having been thus described and illustrated, what is claimed as new and useful and is desired to be secured by Letters Patent is:

1. A method for completing an oil well which comprises lowering into the well a prefabricated pack of aggregate embedded in a filler immiscible with an aqueous fluid, disposing said pack opposite the producing formation between the latter and the producing string, removing the filler from the pack and flowing the well.

2. A method according to claim 1 in which the filler is a plastic material, the viscosity of which decreases with an increase in temperature and is sufficiently low at the temperature of the producing formation to permit it to be moved by a pressure differential across the pack of aggregate.

3. A method according to claim 1 in which the filler is a gel containing bacteria which causes the gel to liquefy after a predetermined period of time.

4. A method according to claim 1 in which the filler is a petroleum grease.

5. A method for completing an oil well which comprises lowering into the well filled with drilling fluid a prefabricated pack of aggregate embedded in a filler immiscible with an aqueous fluid, disposing said pack opposite the producing

formation between the latter and the producing string while maintaining an equal pressure on either side of the pack, establishing a pressure differential across the pack sufficient to remove the filler therefrom, and flowing the well.

6. A method for completing an oil well which comprises lowering into the well filled with a drilling mud a prefabricated annular pack of aggregate embedded in a filler immiscible with an aqueous fluid, locating said pack opposite the producing formation between the latter and the producing string, flushing the mud out of said well from the space between said pack and said formation, sealing off the exterior of the pack from the remainder of the bore hole, establishing a pressure differential between the exterior of the pack and the interior thereof, and flowing the well.

7. A method according to claim 6 in which the pressure differential is created by swabbing the producing string.

8. A method according to claim 6 in which the filler is a grease immiscible with water and having a viscosity which, at the temperature of the producing formation, is such as to permit the grease to be moved by a pressure differential across the pack.

9. A prepacked liner for wells comprising an annular chamber, a filling therefor comprising aggregate embedded in a filler immiscible with water, a back pressure check valve at the lower end of said liner and a packer on the exterior of the upper end of said liner.
